(57) **CLAIM**

The ornamental design for a multi-flow dispenser stopper, as shown and described.

DESCRIPTION

FIG. 1 is a top isometric view of a multi-flow dispenser stopper in accordance with the new design;

FIG. 2 is a bottom isometric view thereof;

FIG. 3 is a rear view thereof;

FIG. 4 is a front view thereof;

FIG. 5 is a right side view thereof and it is understood that the left side is a mirror image thereof;

FIG. 6 is a top view thereof; and,

FIG. 7 is a bottom view thereof.
